UNITED STATES PATENT OFFICE.

ADAM BOOTRYM, OF SCRANTON, PENNSYLVANIA.

DESIGN FOR A FRAME.

61,081.

Specification for Design. Patented June 20, 1922.

Application filed February 9, 1922. Serial No. 631. Term of patent 7 years.

To all whom it may concern:

Be it known that I, ADAM BOOTRYM, a citizen of Poland, and a resident of Scranton, in the county of Lackawanna and State of Pennsylvania, have invented a new, original, and ornamental Design for a Frame, of which the following is a specification, reference being had to the accompanying drawing, forming part thereof.

The figure is a front view of a picture or mirror frame showing my new design.

I claim—

The ornamental design for a frame as shown.

ADAM BOOTRYM.
